UNITED STATES PATENT OFFICE

101,954

DESIGN FOR A MEDALLION

Mary C. Holmes, New York, N. Y.

Application September 23, 1936, Serial No. 64,981

Term of patent 7 years

To all whom it may concern:

Be it known that I, Mary C. Holmes, a citizen of the United States, residing at 19 West 55th Street, New York, New York, have invented a new, original, and ornamental Design for a Medallion, of which the following is a specification, reference being had to the accompanying drawing, forming a part thereof.

Fig. 2 is a side elevational view thereof.

Fig. 3 is a rear elevational view thereof.

I claim:

The ornamental design for a medallion, as shown.

MARY C. HOLMES.
